UNITED STATES PATENT OFFICE.

GEORGE WELCH, OF PERTH, WESTERN AUSTRALIA, AUSTRALIA.

WINDSCREEN.

Application filed April 18, 1922. Serial No. 554,485.

To all whom it may concern:

Be it known that GEORGE WELCH, of Perth, in the State of Western Australia, Commonwealth of Australia, has invented 5 an Improvement in Windscreens, of which the following description, in connection with the accompanying drawing, is a specification, like characters on the drawing representing like parts.

10 This invention relates to improvements in windscreens, and particularly relates to improvements in double screens.

The present invention has two primary objects, namely, firstly, to provide a double 15 windscreen which is supported only at two points and in which the screen sections are capable of any relative adjustment, and secondly, to provide a screen permitting a glare-proof section being turned into the 20 upper road-viewing position.

The invention can be broadly stated as comprising a double windscreen, both sections of which can turn about and can be held in any position relative to a common 25 axis, whereby it becomes possible to completely reverse or alter the relative positions of the upper and the lower sections of the screen.

To enable the invention to be more readily appreciated, reference will now be made 30 to the accompanying drawings showing a preferred embodiment thereof. These drawings must not, however, be construed as limiting the scope of the invention, which 35 will be more particularly defined in the appended claims.

In the drawings:—

Figure 1 indicates a front elevation of one side of the double windscreen, mainly in 40 section except the anti-glare portion and its appurtenant parts.

Figure 2 is a side elevation, looking from right to left, of the supporting standard that forms part of Figure 1.

45 Figure 3 is a front elevation of such supporting standard.

Figure 4 is a side elevation of the coned washer, and

50 Figure 5 is a front elevation of such coned washer.

Referring to the drawings, 10 indicates one of the supporting standards carrying the sashes 11 and 12, of which the former holds the glare-proof, while the latter supports the clear glass. As shown, the double 55 screen is in the position necessary when

driving under glaring conditions, that is to say, the anti-glare section forms the upper or road-viewing screen.

The supporting standard is suitably enlarged near its centre, and in such enlargement there are internally fashioned two conical holes 13 and 14, one commencing on each side, such conical holes being connected by a passage. In the conical hole 13 there is held a conical washer 15 which is slotted at 16. The conical hole 14 has a double truncated cone 17 held against its face, such double truncated hollow cone being in shape similar to a hollow cone truncated at apex 70 and base. A truncated cone 18 is held against the inner peripheral surface of the double truncated hollow cone 17, and such cone (18) has a bolt 19 integral with or connected thereto as an extension in the axial direction. The shank of the bolt 19 is formed so that it clears the double truncated hollow cone 17 as well as the passage connecting the conical holes 13 and 14, whilst it conforms to the slot 16, and therefore causes the cone 18 and coned washer 15 to be positively connected if rotation takes place. Near its end the bolt is threaded in the conventional manner, and turning on such thread is a wing nut 20 by 85 means of which a pressure can be exerted against the coned washer 15, a spring washer 21 being preferably interposed. The effect caused by tightening the nut 20 is that the cone 18 is pulled against the 90 inner peripheral surface of the hollow double truncated cone 17, whilst the outer peripheral surface of the latter is pulled against the surface of the conical hole 14, the conical washer being simultaneously 95 pulled against the face of the other conical hole 13. This means, of course, that there are three pairs of conical frictional surfaces brought into operative juxtaposition.

The double truncated hollow cone 17 and the cone 18 both have formed integrally therewith lateral extensions 22 and 23 respectively, and such extensions are connected to and thereby support the sashes. These extensions are each provided with stops (not shown) that prevent the sashes being turned nearer to each other than about 90 degrees, although otherwise relative movement is not interfered with.

In operation the double windscreens functions as follows:—

When it is desired to move one or both

sections of the screen the wing nut 20 is loosened on each side, whereby the frictional resistance between the various conical surfaces is diminished. This means that the 5 top screen and its sash 11 can be turned, an action which also turns the cone 18, bolt 19, and coned washer 15. In a similar manner the lower screen and sash 12 can be turned, a motion that is of course transmitted to 10 the hollow truncated cone 17. It will be apparent that the separate movement of the screen sections will permit a large number of positions to suit varying atmospheric conditions. In addition, the relative positions of the two screen sections can be 15 completely reversed, which means that if glaring conditions no longer prevail, then the clear screen section can be placed in the upper position, or conversely. When the 20 desired screen adjustment has been made, the wing nuts are tightened, whereby considerable pressure is set up between the various conical surfaces with a corresponding increase in the frictional resistance to displacement.

I claim—

1. A windscreens comprising the combination of supporting standards; a screen section; a hollow cone attached thereto bearing 30 against a conical surface on its outer face; another screen section, a cone attached thereto bearing against the inner face of the hollow cone; and means whereby the conical bearing faces can be held in frictional contact so that the screen sections 35 may be supported in any desired relative positions.

2. A windscreens comprising the combination of supporting standards; a conical hole formed in a standard; a double truncated hollow cone fitting against the peripheral surface of the said conical hole; a screen section attached to the double truncated hollow cone; a cone fitting against the inner peripheral surface of the aforesaid double truncated hollow cone; a screen section attached to the said cone; a bolt integral with the cone; a washer surrounding the bolt shank on the other side of the standard, and a nut whereby the cone and washer can be pulled together and thereby cause frictional contact between the relatively movable conical faces.

3. A windscreens comprising the combination of a supporting standard; a conical hole commencing at one side of the standard; another conical hole commencing at the other side of the standard, the said holes having a common axis and joining at the centre; a double truncated hollow cone fitting against the peripheral surface of one conical hole; a screen section attached to the double truncated hollow cone; a cone fitting against the inner peripheral surface of the double truncated hollow cone; a screen section attached to the said cone; a bolt integral with the cone; a conical washer fitting in the other conical hole, and a nut whereby the cone and conical washer can be pulled together and thereby cause frictional contact between three pairs of relatively movable faces.

Dated this 27th day of February, 1922.
GEORGE WELCH.
